UNITED STATES PATENT OFFICE.

FREDERICK S. DENISON, OF MINNEAPOLIS, MINNESOTA, ASSIGNOR TO MINNEAPOLIS
HEAT REGULATOR CO., OF MINNEAPOLIS, MINNESOTA, A CORPORATION OF MINNE-
SOTA.

SWITCH MECHANISM.

Application filed August 7, 1922. Serial No. 580,359.

To all whom it may concern:

Be it known that I, FREDERICK S. DENISON, a citizen of the United States, resident of Minneapolis, county of Hennepin, State 5 of Minnesota, have invented certain new and useful Improvements in Switch Mechanisms, of which the following is a specification.

This invention relates to improvements in switch mechanisms. This novel switch 10 mechanism is adapted for use as a circuit-changing means and constitutes an improvement upon a switch mechanism disclosed in the prior pending application of the inventor hereof, Serial No. 427,851, filed December 15, 1920. This mechanism is adapted for substantially the same uses as the switch mechanism disclosed in the prior application above mentioned. An example of a specific 20 use of this invention is in temperature regulating systems wherein the heat-generation of a furnace is thermostatically controlled by means of an electric circuit adapted to start or stop the motor controlling parts of the heat-producing medium. In the embodiment of 25 the invention here disclosed, a switch is automatically operated by a secondary circuit of relatively low voltage. The switch controls the primary higher voltage or motor circuit. The switch medium is selectively operated 30 by electro-magnets to control the primary circuit. More specifically, an armature is selectively actuated upon energization of an electromagnet in a secondary circuit through a circuit-closer and this armature not only 35 functions to change the primary circuit but it also functions to interrupt the secondary circuit and to present another secondary circuit adapted to be closed by subsequent circuit-closer movement whereby the armature 40 is oppositely moved to reverse the previous primary circuit condition. In this improved form the movable contacts of the primary switch and secondary switch are mounted upon a single instrumentality pivotally 45 borne by the frame for oscillation by the armature.

The object, therefore, of the invention, is to provide an improved switch mechanism.

Other objects of the invention will more 50 fully appear from the following description and the accompanying drawings and will be pointed out in the annexed claims.

In the drawings there has been disclosed a structure designed to carry out the objects of the invention, but it is to be understood 55 that the invention is not confined to the exact features shown, as various changes may be made within the scope of the claims which follow.

In the drawings:

Figure 1 is a view in side elevation of the mechanism;

Figure 2 is a view in end elevation thereof;

Figure 3 is a fragmentary view in plan of 65 the portion of the switch carrying the movable contacts;

Figure 4 is a partial vertical sectional view on the line 4—4 of Figure 3;

Figure 5 is a detailed fragmentary view 70 in side elevation of the connection between the armature and rock-shafts; and

Figure 6 is a wiring diagram.

In this selected embodiment of the invention the switch mechanism is preferably 75 supported by a frame which comprises a pair of arched side plates 7 and 8 secured to each other in spaced relation. Each leg of each plate is provided with a short flange 9 adapted to rest upon or to be screwed to a 80 bracket 11 carried by a panel frame 12.

Three sets of movable contacts are borne by the frame, one set to open and close a primary or relatively high voltage circuit and the other two sets are adapted singly to 85 present two secondary circuits to a circuit-closing means, such as a thermostat. Each of said sets has a movable contact and all movable contacts are mounted for simultaneous operation by means of a single 90 armature movable in opposite directions in accordance with movements of the thermostat or other circuit-closing means. Electro-magnets are oppositely carried by the frame and the armature depends therebetween so 95 that upon energization of either electromagnets the armature is thereby moved and all contacts operated.

In the disclosed construction, the movable contacts are all operated by a member 100 fast on a shaft 14 journaled in alined apertures in the crown portions 15 and 16 of the opposed arched side plates 7 and 8. The shaft 14 has fixed thereto a hub 17 adapted

to be turned by means of the armature. Preferably, this operable connection is effected by means of the adjacent flanges 19 formed upon the adjacent face of the hub 5 and having a pin 21 projecting through alined holes on the flanges and extending across the space between the flanges. This pin 21 is received within a slot 22 (Figure 5) presented by the arm 23 of the bell 10 crank lever pivotally mounted on the frame plates by means of the pin 24. Spacing blocks 25 are also mounted on the pin 24 on either side of the lever. The other arm 27 of this lever depends between two opposed electromagnets carried by the frame and functions as an armature. These electromagnets are angularly U-shaped and are formed of laminated metal as shown in Figure 2. The base of each electromagnet is 20 secured between adjacent legs of the side plates and held therebetween by means of the screws 28. The polar arms 30 of the electromagnets project horizontally toward each other and are terminally spaced apart 25 a distance sufficient to permit the desired amplitude of movement of the armature and close enough to obtain the desired strength of magnetic field set up by either magnet upon energization by an electric current. 30 Coils 10 and 20 are mounted one upon each of the lower arms of the electromagnets. These coils are adapted to be selectively and singly energized so that the armature is drawn toward the energized coil. Movement of the armature imparts torque to the 35 hub and shaft 14 whereby the movable contacts are operated.

The fixed contacts are three in number and are conveniently carried by one of the 40 side plates to project outwardly from one side of the frame. A piece of strap iron is bent into angularly U-shaped form and its base 31 is held to the side plate 8 by means of the screw 32 so that the upper 45 and lower legs project horizontally to provide an upper bracket 33 and a lower bracket 34.

Binding posts 35 and 36 are mounted 50 upon the upper bracket 33 and downwardly project therethrough being insulated therefrom by the insulation 37. The lower end of the post 35 downwardly presents a contact 38 while the post 36 similarly presents a contact 39. A binding post 41 is 55 mounted upon the lower bracket 34 and upwardly projects therethrough being insulated therefrom by insulation 42. The upper end of this post 41 upwardly presents a contact 43 in opposed spaced relation to the 60 contact 38 of the upper post 35. A detent to limit the throw of the member carrying the movable contacts is provided by the screw 44.

The three movable contacts are carried 65 by a single member fast at one end to the

shaft and adapted to oscillate therewith. The shaft end of this member comprises a disk 45, fast on the rock-shaft 14, and having a rectangular head 46. Two similar narrow metallic side strips 47 are secured 70 at one end to the head by means of screws 48 and 49 passing through the two strips and the embraced head. The strips are both insulated from the head by means of the insulation 51. The other ends of the strips 47 bear inwardly projecting pins 52 received loosely within apertures in the inner ends of the spaced strips 53 integrally joined at their outer ends to form a plate 54. The contact 55 is carried by the plate 54 and projects above the upper surface thereof. The inner end portion of the plate 54 is apertured to receive therein the end 75 of a tension spring 56. The other end of this spring is hooked about the spacing rod 57 carried between the strips 47. Thus when the rock-shaft is turned from the full line position shown in Figure 4 to the dotted line position, the axis of tension of the spring passes through the axis of the pins 52, pivotally joining the pairs of spaced strips 47 and 53. This passage through the line of centers tends to cause the plate 54 to snap from the elevated position shown 80 in full lines to its depressed dotted-line position, thus effecting a sharp, quick break. This plate contact 55 is adapted to make and break with the contact 39 of the post 36. The two other movable contacts are carried 85 by a metallic flange 58 secured to, and insulated from one of the strips 53, preferably the outer. This is placed between insulation 59 and secured to the outer strip 53 by the screws 61 and 62. A backing plate 63 is preferably interposed between the screw-heads and the adjacent insulation. The outer end of the finger is outwardly offset and flattened to present a disk 64 between the opposed fixed contacts 38 and 43. This 90 disk is provided with contacts upon both faces, the contact 65 being upon the upper face while the contact 66 is upon the lower face.

A mode of employing this improved switch mechanism may readily be explained by means of the wiring diagram Figure 6. The employment here suggested is in connection with a thermostat and thermostatic circuit whereby thermal changes may open and close an electric circuit such, for example, as to cause the starting and stopping of an electric motor.

The electric motor 67 is connected in series in a circuit which may be termed the primary circuit and which is provided by the wires 68 and 69 terminally connected to the feed lines 71 and 72 providing electric energy from a suitable source, such, for example, as the usual 110 volt lighting circuit. This primary or motor circuit is adapted to 100

be opened and closed by means of the contact 55 when moved away from, or into engagement with the fixed contact 38. In Figure 1, the primary circuit is shown as 5 broken between the contacts 38 and 55, while in Figure 6 the primary circuit is shown as closed.

As above noted, the movable contacts are simultaneously moved by turning of the 10 rock-shaft 14 upon energization of one of the electromagnets to attract the armature 27. Electric energization of the electromagnets is effected thermostatically. This mechanism is such that, upon energization of 15 a selected electromagnet and movement of the armature thereto, the energizing circuit is immediately broken and another circuit presented through the other electromagnet to be closed upon subsequent movement of 20 the thermo-bar.

The thermostatic circuit is preferably operated by a lower voltage provided by a transformer 73 conveniently located upon the panel frame 12. The main lines 71 and 25 72 are connected to the primary terminals thereof while the wires 74 and 75 lead from the secondary terminals thereof. The wires 74 and 75 are connected to posts 76 and 77 on the panel. The wire 78 connects the posts 20 76 to the screw 62 and therefore to both contacts 65 and 66. Thus connection is had between one secondary terminal and the contacts 65 and 66. The other secondary is connected by its wire 75 with the wire 79 of 30 the thermostat bar 81 which is of any suitable type and is adapted at different temperatures to effect electrical connection with either of the two contacts 82 and 83 of the two sides of the thermostatic circuit. The 35 contact 82 is connected by the wire 84 to the panel post 85 and by the wire 86 to the electromagnetic coil 20. The other end of this coil is connected by the wire 87 to the contact 43 and thus a secondary circuit may 40 be closed by electrical engagement of the movable contact 66 with the contact 43.

In the position of the apparatus shown in Figure 6, it may be assumed that the motor is employed in connection with a heating 50 plant which, as the motor is shown running, has produced heat adjacent the thermo-bar 81 to cause it to bend to connect its wire 75 from one side of the secondary circuit with the hot side contact 83, whereupon the current 55 traverses the wire 88 to the panel post 89 thence by the wire 91 to the coil 10, thence by the wire 92 to the contact 65 to the contact 66, wire 78, post 76 and wire 74 to the transformer. The coil 10 is thus energized, the armature 27 drawn thereto and the contact 55 is thus moved from the contact 38 and the motor circuit thus opened while the contact 65 is likewise moved from the contact 66, thus opening the thermostatic 60 circuit through the coil. The apparatus is 65

then set for the similar motor, starting operation upon movement of the thermo-bar to the cold side contact 82.

I claim as my invention:

1. An electric switch mechanism including a frame, electromagnets on the frame, an armature pivoted on the frame between the electromagnets to be selectively shifted in reverse directions thereby, a rock shaft on the frame, a link connecting said armature and said rock shaft, an oscillatable arm on said shaft parallel to said link, a primary circuit contact carried by said arm, contacts for secondary circuits carried by said arm and insulated both from the arm and the primary contact, fixed primary and secondary contacts carried by said frame in position to be contacted by said contacts on said oscillatable arm. 70 75 80

2. An electric switch mechanism, including a frame, a rock-shaft on the frame, an arm secured to and projecting from the shaft, opposed brackets projecting from one side of the frame, a primary circuit contact fixed to one bracket, and two secondary circuit contacts fixed each to, a bracket in opposed relation, a member mounted to rock on said frame, a primary circuit contact on said member adapted to make and break the primary circuit through said fixed primary contact, contacting means adapted alternately to engage the fixed secondary contacts to complete a circuit through one and simultaneously to break the circuit through the other, an armature movably mounted on 90 95 100 said frame to rock said member and thereby operate all said member contacts, and electromagnets on said frame and adapted upon selective energization to move the armature in different directions, whereby both the 105 members are selectively rocked. 100

3. An electric switch mechanism including a frame, fixed primary and secondary circuit contacts on the frame, an arm mounted to rock on the frame, a fixed primary circuit contact on the frame, two fixed contacts for two secondary circuits on the frame in opposed spaced relation, a movable primary contact mounted on said arm and movable second circuit contacting means on said arm, both said contact and contacting means being insulated from one arm and each other, whereby the contacts are adapted upon rocking of said arm to change the three circuits, electromagnets, an armature movably mounted on the frame and adapted to rock said arm, electromagnets on the frame and adapted upon selective energization to move the armature and thereby 110 115 120 change the position of all said contacts. 125

4. An electric switch mechanism including a frame, electromagnets on the frame, an armature pivoted on the frame between the electromagnets to be selectively shifted in reverse directions thereby, a rock shaft on 130

the frame, a connection between said armature and shaft to oscillate the shaft, a pair of spaced arms insulatedly mounted on said shaft, a contact member pivotally mounted 5 between said spaced arms, contacts on opposite sides of said contact member, spaced contacts on said frame opposite said contacts on said contact member, and a coiled spring arranged between said spaced arms

and connecting the rear end of the latter 10 with said contact member, said spring being constructed and arranged to hold said contact member into shifted position on opposite sides of the pivot connecting said contact arm to said spaced arms.

In witness whereof, I have hereunto set my hand this 4th day of August, 1922.

FREDERICK S. DENISON.
